OTTO HEINIGKE.

UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 13,302, dated September 19, 1882.
Application filed August 11, 1882. Term of patent 3½ years.

To all whom it may concern:

Be it known that I, OTTO HEINIGKE, of New Utrecht, in the State of New York, have invented a new and original Design for Carpets, 5 of which the following is a specification.

This invention relates to a new and original design for carpets and similar fabrics; and it consists in the novel grouping and configuration of figures hereinafter more fully described.

10 The accompanying photograph illustrates a face view of a carpet having my new design.

A is a scattered group, consisting of a large rose and bud and small flowers and leaves on the right, a leaf and blossom cluster on the 15 left, and a cluster of open flowers and leaves on the left above, with a tendril-like bud-spray below, and smaller tendril and bud and leaf sprays on all sides.

B is a group consisting of a central rose with 20 star-shaped flowers and leaves, and has a bud-spray to the left below.

C is a group consisting of two small flower clusters arranged on a common stem, and having tendril-like projections on all sides.

D is a group consisting of large open flowers 25 and small surrounding leaf and tendril sprays. Smaller groups of flowers and circular and right-lined figures loosely fill in the rest of the design, the small creeper or tendril like figures being the chief characteristic of the design. 30

I claim—

1. The design for carpets, consisting of the group A, substantially as shown.
2. The design for carpets, consisting of the group B, substantially as shown.
3. The design for carpets, consisting of the group C, substantially as shown. 35
4. The design for carpets, consisting of the group D, substantially as shown.
5. The design for carpets, consisting of the groups A, B, C, and D and the intervening groups and figures, substantially as shown and described. 40

OTTO HEINIGKE.
